UNITED STATES PATENT OFFICE

170,831

HELMET

Louis H. Pfohl, Forest Hills, N. Y., assignor to Design Center Inc., Long Island City, N. Y., a corporation of New York

Application April 1, 1953, Serial No. 24,304

Term of patent 3½ years

(Cl. D3—13)

To all whom it may concern:

Be it known that I, Louis H. Pfohl, a citizen of the United States of America, and a resident of Long Island City, New York, have invented a new, original, and ornamental Design for a Helmet, of which the following is a specification, reference being had to the accompanying drawing, forming a part hereof.

Fig. 1 is a side view of a helmet embodying my new design;

Fig. 2 is a front view of the helmet shown in Fig. 1;

Fig. 3 is a top view; and

Fig. 4 is a rear view thereof.

I claim:

The ornamental design for a helmet, as shown.

LOUIS H. PFOHL.
